UNITED STATES PATENT OFFICE.

QUINT G. EDDINS, OF RICHMOND, VIRGINIA.

SASH-HOLDER.

1,153,773.

Specification of Letters Patent. Patented Sept. 14, 1915.

Application filed January 19, 1914. Serial No. 813,024.

To all whom it may concern:

Be it known that I, QUINT G. EDDINS, a citizen of the United States, residing at Richmond, in the county of Henrico and State of Virginia, have invented certain new and useful Improvements in Sash-Holders, of which the following is a specification, reference being had therein to the accompanying drawing.

10 My invention relates to sash holders of the spring type, in which the spring is located at some point or points between the window frame and the sash frame and either presses against one of the sashes, or 15 presses the sashes or portions thereof toward each other, whereby there is sufficient friction between the parts to maintain the sash in any adjusted position.

15 Stated in terms of its specific embodiment which will be hereinafter described, my invention comprises a flat metal strip or spring located between parts which move upon each other, as for example the sash and the frame; this spring having a length greater than the length of the moving part which 25 passes over it, and being secured at its opposite ends to points on a relatively fixed part, the distance between which is less than the length of the spring. With this construction a bulge must always exist at some part 30 of the length of the spring, so as to produce sufficient friction to hold the movable member or sash in any desired position.

35 In the accompanying drawings I show the best form of my invention now known to me, but I desire to have it understood that the invention may be given many forms by those skilled in the art, without departing in any way from its generic principle.

40 Of the drawings, Figure 1 is a vertical transverse section of a window frame showing upper and lower sashes in closed positions, Fig. 2 is a similar section showing the lower sash raised, and the upper sash lowered, and Fig. 3 is a plan view of the spring strip constituting the sash holder proper.

45 Referring to Figs. 1 and 2, the window frame is designated 10, the usual parting beading by 11, and the inner and outer sash stops 12 and 13. Between the inner sash stop 12 and the parting beading 11 is positioned the lower sash, while between the parting beading 11 and the outer sash stop 13 is positioned the outer sash 15. The relative positions of the sash stops and the parting beading are made such, that the sashes

14 and 15 under all conditions have ample freedom of movement up and down. Under such conditions, there is not sufficient swelling under change of weather conditions, or 50 slight warping of the stops, beading, or sash frames, to bind the sashes. Interpolated between the sash stops 12 and 13 respectively and the sashes 14 and 15, are the sash holders 16 of my invention. In this embodiment 55 they are secured to the inner edges of the sash stops at points 17 and 18 spaced apart a distance less than the extended length of the strip between them, whereby, that portion of the strips 16 adjacent the sash being 60 pressed flatly against the edge of the sash stop, there is when the sashes are in the position of Fig. 1, a bulged portion above and below the lower and upper sashes 14 and 15 respectively. 65

70 The strips 16 are preferably of smooth tempered steel, such as clock spring steel, but they may be made of bronze, brass or any other material, smoothly finished to the requisite degree, the smoothness of the finishing being varied to produce greater or less amount of friction if desired. Each sash is 75 strongly pressed, by the bulged portion of strip 16 against the parting beading, thus forming a weather-proof joint between the 80 sash and the beading in each case. This joint is sufficiently tight not only to prevent the entrance of dust and dirt under fair weather conditions, but to prevent the entrance of moisture and water during the 85 stormiest of weather. When the sashes are 90 moved, the bulge of the strip 16 at the one end disappears, and another bulge appears at the opposite end, the strip during the raising or lowering of the sash, as the case 95 may be, sliding past the face of the sash frame. In other words, the flattening out of the bulge at one end of the strip by the movement of the sash, gives rise to a longitudinal movement of the body of the strip 100 with respect to the sash stop or other fixed part to which it is secured. The smoothness of the spring strip 16 should be sufficient to permit this to take place easily. Therefore 105 when the sashes are moved from their normal positions, to positions such as shown in Fig. 2, the sash is pressed flatly against the parting beading by bulged portions both above and below it, and the bulged portions retain the sashes in their adjusted positions, 110 the weight of the sash being insufficient to eliminate the bulged portion on the under

side, and overcome the friction between itself and the parting beading. I have found that a sash holder of this type to hold a sash of the usual size and weight may be made from a spring strip of very small width, and very light weight, such as the ordinary clock spring strip. Obviously by simply increasing the size and weight of the strip, the sash holder may be made suitable 10 for retaining in position sashes of any desired size whatsoever.

As above pointed out, the holding power of the bulged portions of the strip depends primarily upon the resistance to longitudinal 15 movement of the strip with respect to the sash stop or other fixed part to which it is secured, and this movement may not only be varied by varying the smoothness of the strip itself, but the smoothness of the adjoining faces of the sash holder and sash 20 stop, as well as the closeness of the space between the sash and the sash stop may likewise be adjusted to vary this holding power. Attention need be paid to these matters however principally in sash holders of the very 25 largest sizes.

Copies of this patent may be obtained for five cents each, by addressing the "Commissioner of Patents, Washington, D. C."

Obviously the sash holder of my invention may be applied directly to the window frame 10 *per se* instead of sash stops 12 and 13 secured thereto. In such case, they may 30 bear directly upon the edges of the sash or a beveled portion thereof as in many well known forms of the spring type of sash holder.

What I claim is:

The combination of a frame, a sash sliding therein, and a spring between the sash and frame, having its ends secured to points on the frame spaced apart a distance less than the length of the spring, whereby a portion of said spring will form a projecting bow above or below the bearing surface of the sash, or both, according to the direction of movement and position of the sash, to hold the same.

In testimony whereof I affix my signature in presence of two witnesses.

QUINT G. EDDINS.
